US0D1031027S

(12) **United States Design Patent** (10) **Patent No.:** **US D1,031,027 S**
(45) **Date of Patent:** **** Jun. 11, 2024**

(54) **ATTACHMENT ARM**

(71) Applicant: **NeuWave Medical, Inc.**, Madison, WI (US)

(72) Inventors: **Louis Mingione**, Madison, WI (US); **Daniel Price**, Madison, WI (US); **Kevin Royalty**, Madison, WI (US); **Jeffrey Bissing**, Madison, WI (US); **Samantha Weber**, Madison, WI (US); **Derek Rund**, Madison, WI (US); **Michael Palmisano**, Madison, WI (US); **Brennan McCabe**, Madison, WI (US); **Hunter Elmore**, Madison, WI (US); **Mary Friedl**, Madison, WI (US); **Josh Haldeman**, Madison, WI (US)

(73) Assignee: **NeuWave Medical, Inc.**, Madison, WI (US)

(**) Term: **15 Years**

(21) Appl. No.: **29/823,552**

(22) Filed: **Jan. 18, 2022**

(51) LOC (14) Cl. **24-02**

(52) U.S. Cl.

USPC **D24/127; D15/199**

(58) Field of Classification Search

USPC D8/14, 314, 374, 394; D15/199;

D24/143, 127-131, 133, 186, 108

CPC A61B 1/0052; A61B 1/0057; A61B 1/018;

(57) **CLAIM**

The ornamental design for an attachment arm, as shown and described.

DESCRIPTION

FIG. 1 is a perspective view showing our new design of an attachment arm;

FIG. 2 is a front view thereof;

FIG. 3 is a rear view thereof;

FIG. 4 is a bottom view thereof;

FIG. 5 is a top view thereof;

FIG. 6 is a side view thereof; and,

FIG. 7 is a different side view thereof.

Any broken line illustration of environmental structure in the drawings is not part of the design sought to be patented.

1 Claim, 7 Drawing Sheets
